DESIGN FOR A HOLDING CLIP FOR PHOTOGRAPHIC NEGATIVES AND PRINTS

Martha Greig, New York, N. Y.

Application August 10, 1939, Serial No. 86,579

Term of patent 7 years

To all whom it may concern:

Be it known that I, Martha Greig, a citizen of the United States, residing at New York, in the county of New York, State of New York, have invented a new, original, and ornamental Design for a Holding Clip for Photographic Negatives and Prints, of which the following is a specification, reference being had to the accompanying drawing, forming a part thereof.

Figure 3 is a perspective view of the clip looking from the back of Figure 1, with the clip in open position ready to receive a negative or print.

I claim:

The ornamental design for a holding clip for photographic negatives and prints, as shown and described.

MARTHA GREIG.
